UNITED STATES PATENT OFFICE.

FREDRICK H. SCHINNEER, OF CHICAGO, ILLINOIS, ASSIGNOR TO THE CHICAGO HANDLE-BAR COMPANY, OF SAME PLACE.

DESIGN FOR A BICYCLE HANDLE-BAR.

SPECIFICATION forming part of Design No. 27,835, dated November 9, 1897.

Application filed September 20, 1897. Serial No. 652,389. Term of patent 3½ years.

To all whom it may concern:

Be it known that I, FREDRICK H. SCHINNEER, a citizen of the United States, residing at Chicago, in the county of Cook and State 5 of Illinois, have invented and produced a certain new and original Design for Bicycle Handle-Bars, (Case No. 1,) of which the following is a description, reference being had to the accompanying drawings, forming a part of 10 this specification.

Figure 1 of the said drawings illustrates the bicycle handle-bar in side elevation. Fig. 2 is a top view of the same. Fig. 3 is a view in front elevation, and Fig. 4 is a section on 15 any right plane extending through the bar *b*.

The characteristic features of the design herewith shown and described consist in the configuration and curvature of the handle-bar from the stem to the handles or grips 20 mounted at its extremities and somewhat widely separated from one another.

The handle-bar of my design is symmetrical with respect to the head-post or stem *a*, with which connection is made to the front 25 fork and steering-wheel of the bicycle.

Tubing having octagonal form is used for shaping the bar *b*, which is mounted at its mid-length upon the stem or head-post.

From the stem *a* the bar curves downward 30 and outward to point *c*, considerably beyond a plane coincident with the front of the said stem with which the bar *b*, through this arc, viewed from the side, forms an interior angle approximately of twenty degrees, as seen in 35 Fig. 1. From the point *c* the bar extends slightly downward to point *d* and is bent ab-

ruptly to the rear, forming nearly the arc of a quadrant, enlargements or grips *e* being mounted upon the ends of the bar. The said grips and the ends of the bar accordingly 40 are somewhat divergent rearwardly and are widely separated, the same lying in a plane substantially at right angles to and considerably to the rear of a plane coincident with the stem *a* and the axis of the bar. 45

Viewed from the top and in front the elliptical curvature of the bar forward and downward is substantially the same, although the latter curvature is of longer arc, thus bringing the bar in a long graceful sweep in front 50 of and considerably below the top of the stem or head-post, and thence sharply back to the extremities or handles.

By the aid of the several figures of the drawings herewith presented the graceful outline and generally pleasing design of my bicycle handle-bar will be immediately appreciated. 55

Having now described and shown the bicycle handle-bar of my invention, what I 60 claim as new, and desire to secure by these Letters Patent, is—

The design for a bicycle handle-bar substantially as herein shown and described.

In witness whereof I hereunto subscribe 65 my name this 7th day of September, A. D. 1897.

FREDRICK H. SCHINNEER.
